(57) **CLAIM**

We claim the ornamental design for a firearm concealment clip, as shown and described.

DESCRIPTION

FIG. 1 is a rear perspective view of a firearm concealment clip, showing my new design;

FIG. 2 is an exploded front perspective view thereof;

FIG. 3 is an exploded front elevational view thereof;

FIG. 4 is an exploded rear elevational view thereof;

FIG. 5 is an exploded right-side elevational view thereof;

FIG. 6 is an exploded left-side elevational view thereof;

FIG. 7 is an exploded top plan view thereof; and,

FIG. 8 is an exploded bottom plan view thereof.

The broken lines showing a firearm in FIG. 1 depict environmental matter and form no part of the claimed design.
